UNITED STATES PATENT OFFICE.

ELMER S. STACK, OF SOMERVILLE, MASSACHUSETTS.

PIPE-THREADER.

1,147,456.

Specification of Letters Patent.

Patented July 20, 1915.

Application filed March 10, 1911. Serial No. 613,612.

To all whom it may concern:

Be it known that I, ELMER S. STACK, a citizen of the United States, and a resident of Somerville, in the county of Middlesex and State of Massachusetts, have invented 5 an Improvement in Pipe-Threaders, of which the following description, in connection with the accompanying drawings, is a specification, like letters on the drawings 10 representing like parts.

This invention relates to thread cutters and other tools and among other objects provides simple and effective means for guiding the cutter in cutting threads on long or 15 short pipes.

The character of the invention may be best understood by reference to the following description of an illustrative embodiment thereof shown in the accompanying 20 drawing, wherein:

Figure 1 is a side elevation of an illustrative pipe thresher embodying the invention; Fig. 2 is a view looking toward the left of Fig. 1; Fig. 3 is a view looking toward the right of Fig. 1; Fig. 4 is a plan view of Fig. 1; Fig. 5 is a detail view of a die and die stock; Fig. 6 shows a device which may be used in connection with the die stock shown in Fig. 5; and Fig. 7 is a 30 section taken on line 7—7 of Fig. 6.

The illustrative pipe thresher to be described embodying the invention may be used in connection with any suitable pipe holding means, such for example as a vise 35 (Figs. 1 to 4) comprising a body or frame 1 conveniently of sheet material bent into U-shape form, the ends of the legs of the U being riveted or otherwise secured to a U-shaped base plate 3 also of sheet material. 40 On said body are mounted jaws 5 of steel or other suitable material which may be formed to present gripping faces. Herein said jaws are grooved longitudinally presenting sharp corners as shown in Fig. 3 45 adapted to nip a pipe or other device held therebetween and prevent rotation thereof in the jaws as on the cutting of threads on such pipe or device.

To permit the jaws to grip pipes of different sizes they are made relatively adjustable, the lower jaw 5 being shown bolted or otherwise secured on the top of the base plate 3 and in a lateral recess in the body 1. The upper jaw in the present embodiment of 55 the invention is adjusted relatively to the

lower jaw and is adapted to slide along the vertical edges of the recess in the U-shaped sheet body 1. To this end the upper jaw is connected to a screw 7 threaded into a block 9 fitted in the closed end of the U-shape 60 body and suitably secured thereto. The screw 7 may be rotatively connected to the upper jaw in any suitable manner. As shown herein said jaw is provided with a boss projection 11 recessed to receive an end 65 portion of said screw 7 grooved to receive a pin 13 inserted in said boss. By this construction the adjustment of the screw will move the upper jaw relatively to the lower jaw without rotating said upper jaw, the 70 latter being guided along edges of the U-plate. The screw 7 is provided with a suitable handle 15.

A vise such as described is extremely light, small, compact, and cheap in construction 75 permitting it to be readily carried from place to place and set up.

Having described a preferred construction of vise I will now describe means adapted to be used in connection therewith for 80 threading purposes. To this end there is provided a die stock 17 preferably square in shape to conform to and receive a usual die 19 (Fig. 5). Various sizes of dies will be used according to the size of pipe to be 85 threaded. To permit different dies to be readily inserted and removed in said die stock fastening screws 21 are provided threaded into ribs 23 on opposite sides of said die stock. Portions of the heads of the 90 screws are removed so that they may be turned to permit the ready removal of the die. The die stock is provided with a boss 25 bored to receive the stem of a handle 27 adjustably held in said boss by a suitable set 95 screw 29.

Heretofore in threading short pipes considerable difficulty has been experienced in effecting a proper centering of the die owing to the short length of the pipe operated on. 100 Also, die stocks as usually constructed have an elongated boss or sleeve extending in advance of the die to provide for the proper guiding of the latter. The presence of this elongated sleeve makes it impossible to 105 thread short lengths of pipes.

One of the objects of the invention is to eliminate the necessity of such a sleeve and thereby permit the die to work up close to the ends of the jaws in which the pipe is 110

held. To this end a guide member or mandrel 31 is provided (Fig. 7) for coöperation with the die stock and a suitable fixed guide. Herein one end of said mandrel is extended 5 within the die stock and threaded or otherwise secured thereto. The mandrel projects from said boss through the die and beyond the face thereof a substantial distance. Any suitable bearing or guiding arrangement 10 may be provided for the outer free end of this mandrel. Herein there is provided a bracket 33 having one end apertured to rotatively receive a free end of said mandrel, the opposite end of said bracket having an 15 elongated slot receiving a hand screw 35 threaded to the body of the vise, as shown in Fig. 3. By this construction the bracket may be adjusted relatively to the jaws of the vise to permit the proper centering of the 20 mandrel and also to and from operative position. While as shown herein the mandrel is secured to the die stock and slides in said bracket, it will be understood that the mandrel might be fast on said bracket and loose 25 in said die stock.

In use a short length of pipe, such as P, is clamped between the jaws 5 with the portion thereof desired to be threaded projecting beyond the ends of said jaws. Then the 30 die stock is presented to said pipe and the mandrel 31 is thrust through the pipe P and the hole in the bearing bracket 33 until the face of the die engages the end of the pipe. The handle 27 is then rotated to cut the 35 thread on the pipe. By this construction the die will be free to feed along the pipe and cut threads therein close to the ends of the jaws holding the pipe without interference. The die is positively guided by the mandrel 40 and bracket described at a point remote from the die, thereby maintaining the accurate centering of the die and enabling threads to be accurately cut on the pipe. The pipe in no way is utilized to effect the guiding of 45 the die thereon other than at the point of application of the die to the pipe. Thus, the weight of the die stock does not come upon the pipe in a manner tending to strain, mutilate or distort the pipe, as heretofore, where 50 it has been attempted to guide the die stock by devices clamped to and within the pipe.

After the pipe has been threaded the die stock and its mandrel together are withdrawn from the pipe, and the jaws of the 55 vise are separated permitting the removal of the pipe. No other operation is necessary. There are no devices within the pipe to be unclamped and removed.

Where extremely short pipes are being 60 threaded a ring 37 conveniently of a section of pipe corresponding to that to be threaded may be inserted between the jaws of the vise at their ends opposite to that occupied by the pipe to be threaded to keep the jaws of the 65 vise evenly spaced.

In order that the die stock may be readily adapted for threading long pipes as well as short pipes, the mandrel 31 may be removed and a supplemental guide may be provided. Herein this guide comprises a boss 39 having 70 feet 41 which may be held to the die stock by the same screws 21 which hold the die in place in said die stock. The boss 39 may be provided with removal bushings 43 to conform to the exterior diameter of the pipe to 75 be threaded. When the die stock is used in threading pipes which are sufficiently long to make it unnecessary to use the mandrel and guide bracket, the guide 39 is sufficient to keep the die properly centered. 80

While the invention is described in connection with a thread cutter it will be understood that it is applicable to other tools.

It is not indispensable that all of the features of the invention be used conjointly 85 since they may be used separately to advantage.

Having described one embodiment of the invention without limiting the same thereto, what I claim as new and desire to secure by 90 Letters Patent is:

1. A threading device comprising in combination, means for holding an article to be threaded; a die stock; and guiding means for the latter projecting from said die stock 95 to receive support from said holding means.

2. A threading device comprising, in combination, means for holding an article to be threaded; a die stock; a die therefor; supporting means, and guide means projecting from said die stock to said supporting means 100 for positioning said die stock.

3. A threading device comprising, in combination, means for holding a pipe to be threaded; a die stock and its die; supporting means, and a mandrel extending from said die stock through said pipe to said supporting means for positioning said die stock. 105

4. A threading device comprising, in combination, means for holding an article to be threaded; a die stock having a guide mandrel secured thereto; and guiding means on said holding means for said mandrel.

5. A device of the class described comprising in combination a die stock; a die therefor; supporting means; and guide means independent of the article operated on extending from said die stock to said supporting means for positioning said stock. 115

6. A device of the class described comprising in combination, a die stock; a die therefor; a support; and a guide member for insertion through a short pipe independently thereof and connecting said stock and support to guide said stock and die while acting on said pipe. 120

7. A threading device comprising, in combination, a vise having jaws for holding an article to be threaded; a bearing bracket adjustably mounted on said vise adjacent said 130

jaws; a die stock; a die carried thereby for active engagement with one end of an article to be threaded; and guiding means projecting from said die stock beyond the opposite 5 end of said article for guidance by said bearing bracket.

8. A device of the class described comprising in combination, a die stock; a die therefor; a mandrel projecting from said stock 10 for insertion through a short pipe independ-

ently thereof; and means for supporting said mandrel beyond said pipe.

In testimony whereof, I have signed my name to this specification, in the presence of two subscribing witnesses.
